UNITED STATES PATENT OFFICE.

JOHN A. WILLIAMS, OF NEW YORK, N. Y., ASSIGNOR TO THOMAS ADAMS, JR., OF SAME PLACE.

SELF-LIGHTING GAS-BURNER.

SPECIFICATION forming part of Letters Patent No. 627,630, dated June 27, 1899.

Application filed November 26, 1897. Serial No. 659,872. (No model.)

To all whom it may concern:

Be it known that I, JOHN A. WILLIAMS, a citizen of the United States, residing at New York, (Brooklyn,) in the county of Kings and State of New York, have invented certain new and useful Improvements in Self-Lighting Gas-Burners, of which the following is a specification:

My invention relates to automatic gas-lighters, the construction and advantages of which will be hereinafter set forth, reference being had to the accompanying drawings, in which—

Figure 1 is a perspective view of the burner; Fig. 2, a similar view showing the lighting attachment in a different relation to the tip; Fig. 3, a view illustrating a modified form of construction, and Fig. 4 a side elevation showing the operation of the device.

Broadly stated, the object of my invention is to produce a self-lighting gas-burner, one which will automatically ignite the gas and then through the heat produced by the flame withdraw the igniting substance from the path or line of the flame.

It comprises, in combination, a burner, a substance capable of igniting the gas by contact therewith, and a thermostatic device connected to the burner for holding the igniting substance.

Referring to the drawings, and particularly to Fig. 1, A indicates the burner, which may be of the ordinary construction, provided with a perforated lug or projection B, extending from one side thereof. Adjustably mounted in said lug is a rod or bar C, carrying at its upper end a coil D. Said coil is composed of two strips of metal united to each other, the metals possessing different coefficients of expansion, so that when the coil becomes heated it will unwind. The outer end of the coil is extended upward and forms an arm E, to the upper end of which is secured a basket F, containing the substance capable of igniting the gas when coming in contact therewith.

While I have shown in the drawings what I term a "basket," I do not desire to confine myself thereto, as any form of holder may be employed, and, in fact, a body of spongy asbestos impregnated with the igniting com-

ound may be employed, in which case it may not be necessary to employ any basket or surrounding substance.

In the form illustrated in Fig. 1 when the gas is turned on it will come into direct contact with the basket F and ignite. Immediately this takes place the thermostatic action of the coil will be brought into play and the arm E and basket F be withdrawn from the path or line of the flame, as indicated in dotted lines in Fig. 4. With the parts in the relation shown in the said figures the flame will come into direct contact with the coil D and produce a very quick action of the parts. The degree to which the flame will be interfered with by the coil under this form will be found to be very slight—that is, the flame will be cut by the coil, but will be found to reunite as soon as it passes beyond the same. So soon as the gas is turned off the coil will become cool and in so doing will draw the arm and its basket back into line with the opening in the tip of the burner, ready to again ignite the gas when it is turned on.

In Fig. 2 the opening in the tip is shown as standing in a line parallel with the coil, and the coil is below the tip. The basket F or other igniting device is in this instance bent slightly over, so as to be in line with the gas as it issues from the burner; but the action is substantially the same as in the former construction.

In Fig. 3 I have shown two coils the arms of which are connected at the top and carry the igniting device. Under this construction the thermostatic coils may be made of lighter material than in the forms just alluded to. The action, however, is the same.

I am aware that prior to my invention igniting substances have been held in line with the gas issuing from the burner; but in said devices the igniting substance has remained stationary, and consequently been enveloped by or kept in contact with the flame. Under such conditions the substance of necessity deteriorates, and it has been found that such devices will not work successfully for any period of time. I am also aware that means have been employed whereby the igniting substance is normally out of the path of the

flame and is designed to be manually brought in line therewith and afterward withdrawn through the agency of a spring, a weight, or the like. I am not aware, however, that previous to my invention any one has applied an igniting device to a burner in such manner that when the gas is ignited the igniting substance, which normally stands in the path of the flame, will be automatically and positively withdrawn therefrom by the action of the flame or the heat generated thereby, and I desire to be understood as broadly claiming such idea.

The igniting material to be used may be any of the known compounds or substances which possess the property of absorbing and giving off oxygen and causing combustion, such as sponge platinum, platinum-black, and the like.

Means other than that shown may be employed for holding the coil.

Having thus described my invention, what I claim is—

1. In combination with a gas-burner, an igniting substance therefor, and a thermostatic connection between said burner and the igniting substance.

2. In combination with a gas-burner, an igniting material adapted to ignite the gas by contact therewith, and a thermostatic device carrying said igniting material.

3. In combination with a gas-burner, an igniting material adapted to ignite the gas by contact therewith, and means for supporting said igniting material in line with the flame and for automatically withdrawing said material from the path of the flame when the gas is ignited.

4. In combination with a gas-burner, a ther-

mostatic coil carried thereby, and an igniting material also carried by the coil and held in line with the opening in the burner, substantially as and for the purpose described.

5. In combination with a gas-burner, a thermostatic coil adjustably secured thereto, and an igniting material carried by said coil in line with the opening in the burner.

6. In combination with a gas-burner, a thermostatic coil carried thereby, an arm extending from the free end of the coil, and an igniting material carried by the upper end of said arm in line with the opening in the burner.

7. In combination with the burner A, lug B secured thereto, arm C adjustably mounted within said lug, thermostatic coil D, arm E extending upwardly therefrom, and an igniting material carried by the upper end of said arm.

8. In combination with a gas-burner, a thermostatic coil mounted thereon in line with the opening in the burner and adapted to come in contact with the flame as it issues therefrom, and an igniting material carried by the coil, substantially as described.

9. In combination with a gas-burner, an igniting material adapted to ignite the gas by contact therewith, and means for supporting said material and drawing it into and out of alignment with the flame, said means being controlled in its movement by the heat generated by the flame.

In witness whereof I hereunto set my hand in the presence of two witnesses.

JOHN A. WILLIAMS.
